UNITED STATES PATENT OFFICE.

WILLIAM D. THOMPSON, OF DETROIT, MICHIGAN, ASSIGNEE TO HUTCHINS CAR ROOFING COMPANY, OF DETROIT, MICHIGAN, A CORPORATION OF MICHIGAN.

CAR.

1,137,928.

Specification of Letters Patent. Patented May 4, 1915.

Application filed March 4, 1910. Serial No. 547,354.

To all whom it may concern:

Be it known that I, WILLIAM D. THOMPSON, a citizen of the United States of America, residing at Detroit, in the county of 5 Wayne and State of Michigan, have invented certain new and useful improvements in Cars, of which the following is a specification, reference being had therein to the accompanying drawings.

10 The invention relates particularly to freight cars, and consists in the novel construction thereof, in the peculiar arrangement and combination of parts, and in various details of construction, as will be hereinafter set forth.

15 In the drawings, Figure 1 is a sectional perspective view, illustrating an embodiment of my invention; and Fig. 2 is an end view.

In the drawings thus briefly described, A 20 represents the siding or sheathing of the car, B is a side plate to which the siding is secured, and C is the roof structure.

25 In the present instance, the roof includes metallic carlines D of trough-shaped formation, each formed with laterally projecting flanges E extending beyond the channel body, and at the end with a depending plate section F that extends within a recess G formed for that purpose in the outer face 30 of the side plate, whereby the outer end of the carline will lie flush with the outer face of the plate.

H are plates or sheets forming the metallic covering of the roof, having upstanding flanges I adjoining the upstanding portions 35 of the carline, as shown, and J are cap plates arranged over the carlines and over the flange portions of the sheets. The cap plates are provided with downturned end portions K, and bolts L, extending transversely 40 through the side plate B, the cap, and depending portion of the carline, serve to hold the last two members in place. The metallic sheets are likewise provided with downturned eave portions, as M, and these are 45 secured to the side plate by nails or bolts, as O.

To guard against any damage resulting from side scraping of the car through 50 proper switching and the like, I have provided a guard member, preferably in the form of a metallic plate, extending longitudinally of the car along the upper portion of the siding, and have so positioned the 55 guard strip as to project beyond the roof

and siding to act as a wear plate. On account of the various advantages obtained, as will be hereinafter set forth, I preferably construct the fascia of the car to perform the further function of a guard. The preferable form of fascia is as illustrated, consisting of a metallic bar P of Z-shaped cross section. The upstanding flange portion Q of the fascia adjoining the side plate is held in position by the bolts L. The web portion R projects laterally and outwardly a sufficient distance to extend beyond the siding A, and a depending flange portion S forms in connection with the web a cap section, which embraces the upper edge of the siding. The 60 fascia thus forms a weather guard for the upper edge of the siding, preventing leakage within the car, a housing within which the upper portion of the siding may be removably placed, and a guard extending beyond the car side sufficiently to constitute 65 a wear plate to receive any scraping action that the car may be subjected to. It will also be noticed that by the use of the fascia described the width of the roof is materially 70 lessened, thereby producing a considerable saving in roofing material.

75 As shown in Fig. 1, the flange portion Q of the fascia is interposed between the side plate and the marginal portions of the sheet 80 and sheet caps, and has suitable openings, as a, punched therein to receive the sheet-retaining devices.

85 It will be further noticed from the specific car construction disclosed that the fascia in the present instance forms a structural portion of the roof, and through its cap formation affords means whereby the sheathing may be independently and conveniently removed, either in whole or in part, for repair or replacement; also, that leakage along the eave portion of the roof is effectively prevented by the overlapping of the fascia upon the siding and of the roofing in turn upon the fascia.

90 What I claim as my invention is.—

1. In a freight car, the combination with the siding or sheathing, of the roof structure, and an offset shaped metallic guard member extending longitudinally along the 95 upper portion of the siding and outwardly beyond the latter and the roof.

10. In a freight car, the combination with the frame, the siding, and a roof sheet having a down turned flange, of a combined 11

fascia and wear-iron having offset vertical portions and a lateral portion extending over the upper edge of the siding, one of said vertical portions being positioned between the frame and down turned flange of the roof sheet, and the other vertical portion overlapping the upper end of the siding.

3. In a freight car, the combination with the side plate, of the siding terminating at its upper edge at a distance below the plate top, and forming in connection therewith a

longitudinal angle-shaped channel, a metallic angle bar within the channel covering the upper edge of the siding, and a metallic roofing having its eave portion overlapping 15 the vertical section of the angle bar.

In testimony whereof I affix my signature in presence of two witnesses.

WILLIAM D. THOMPSON.
